UNITED STATES PATENT OFFICE.

EDWARD W. N. BOOSEY, OF DETROIT, MICHIGAN.

DRAINAGE FITTING.

Application filed July 9, 1927. Serial No. 204,543.

This invention relates to drainage fittings and the object of the invention is to provide a floor drain arranged so that seepage through the floor is carried into the drain 5 thus preventing any leakage between floors.

Another object of the invention is to provide a floor drain in which the lead flashing is carried into the drain and caulked in place so that any seepage through the floor or 10 about the drain is carried into the drain outlet.

A further object of the invention is to provide a flanged member having corrugations on the under surface thereon through which 15 seepage is adapted to flow, apertures being provided through which the seepage may pass into the drain outlet.

These objects and the several novel features of the invention are hereinafter more 20 fully described and claimed and the preferred form of construction by which these objects are attained is shown in the accompanying drawing in which—

Fig. 1 is a section through a floor drain 25 embodying my invention.

Fig. 2 is a perspective view of the drain with the lead flashing removed.

Fig. 3 is a perspective view of the corrugated plate which is positioned on the lead 30 flashing.

The drain comprises a cup shaped member 1 having an outwardly extending flange 3. The member 1 is provided with a shoulder 5 and an annular member 6 is positioned on 35 this shoulder as shown in Fig. 1. The member 6 is provided with an inwardly extending threaded flange 7 and a series of apertures 8 are provided through this flange as shown. A threaded sleeve 9 is threaded into 40 the flange 7 and is provided with an enlarged upper end which is closed by the perforated plate 10. A plate 11 is threaded onto the sleeve 9 and a seepage ring 12 is positioned about the periphery of the plate 45 11. This drainage fitting is to be used for a drain in floors through which seepage may occur such as a concrete floor in a shower bath or like construction. To prevent the seepage from passing through the floor a 50 lead plate 13 is provided which extends outwardly to the edge of the floor. This plate is formed from sheet lead which is carried in over the flange 3 and downwardly into the space 14 between the member 6 and the 55 wall of the cup shaped member 1. This space 14 is then filled with caulk in the

top of the member 6 as shown. The seepage ring 12 fits about the plate 11 and the plate 11 as shown in Fig. 3 is provided with radial corrugations on the under side 60 thereof. This plate 11 is threaded downwardly on the sleeve 9 to secure the lead plate between the flange 3 and the member 11. When the concrete floor is laid the parts are in the position shown in Fig. 1. 65 Should any of the water pass through the concrete floor or through cracks in the floor it passes over the lead plate 13 and through the seepage ring 12 and through the corrugations in the plate 11 and thence through 70 the apertures 8 in the member 6 into the drain. By this arrangement the water is prevented from passing through to the floor below and all of the water which seeps through the floor is carried into the drain. 75 For this purpose the edge of the lead sheet or flashing is carried upwardly slightly above the floor level at the outer edges of the floor.

From the foregoing description it becomes 80 evident that the device is very simple and efficient in operation; will not easily get out of order; will carry all seepage through the floor back into the drain, and provides a device which accomplishes the objects described.

Having thus fully described my invention, its utility and mode of operation, what I 85 claim and desire to secure by Letters Patent of the United States is—

1. A drainage fitting comprising a cup shaped member having a peripheral flange at the upper edge and an annular shoulder adjacent the bottom, an annular member positioned on the said shoulder in spaced relation with the wall of the cup shaped member, the annular member having an inwardly extending threaded flange provided with a series of apertures therethrough, a lead flashing extending over the peripheral flange 90 of the cup shaped member and between the annular member and the wall of the cup shaped member, the space between the annular member and the lead flashing being filled with caulk to the top of the annular member, a tubular member, a plate threaded onto the tubular member and having a corrugated under surface, the tubular member being threaded into the flange of the annular member to bring the plate into contact with the 100 lead flashing and a seepage ring positioned 105 on the lead flashing about the periphery of

the said plate, the tubular member at the upper end being formed to provide a drainage inlet.

2. A drainage fitting comprising a cup shaped member having a peripheral flange and an annular shoulder adjacent the bottom, an annular member positioned on the said shoulder and having an inwardly extending threaded flange provided with a series of 5 apertures therethrough, a lead flashing extending over the flange of the cup shaped member and between the annular member and the wall of the cup shaped member, the space between the annular member and 10 flashing being filled with caulking to the top of the annular member, a tubular member threaded into the flange of the annular member and having a drain plate at the upper end, a plate threaded onto the tubular member and having a corrugated under surface resting on the lead flashing and a 15 seepage ring positioned about the periphery of the said plate.

3. A drainage fitting comprising a cup shaped member having an annular shoulder, an annular member positioned on the said shoulder and having an inwardly extending threaded flange provided with a series of 25 apertures therethrough, a lead flashing extending into the cup shaped member between the annular member and the wall of the cup shaped member, a tubular member threaded into the flange of the annular member, a 30 plate threaded onto the tubular member and having a radially corrugated under surface adapted to rest on the lead flashing and a 35 seepage ring positioned about the periphery of the said plate.

4. In a drainage fitting, a cup shaped member having a peripheral flange at the upper edge and an annular shoulder adjacent the bottom, an annular member positioned on the 40

shoulder and having an inwardly extending threaded flange provided with a series of 45 apertures therethrough, a tubular member threaded into the said flange and formed at the upper end to provide a drainage inlet, a plate threaded onto the tubular member and provided with a corrugated under surface and a seepage ring positioned about the 50 periphery of said plate.

5. In a drainage fitting, a cup shaped member having an annular shoulder, an annular member positioned on the shoulder and having an inwardly extending threaded flange 55 provided with a series of apertures therethrough, a tubular member threaded into the said flange, a plate threaded on the tubular member and having a corrugated under surface and a seepage ring positioned about the 60 periphery of the said plate, the upper end of the tubular member being formed to provide a drainage inlet.

6. In a drainage fitting, a cup shaped member having a peripheral flange, an annular 65 member supported thereby and having an inwardly extending threaded flange provided with a series of apertures therethrough, a tubular member threaded into the flange, a 70 plate threaded on the tubular member and contiguous to said peripheral flange, said plate having a corrugated under surface providing drainage grooves, the said structure being adapted to be positioned in a floor of self-hardening plastic material, and porous 75 material so positioned relative to the plate as to prevent the plastic material passing through the drainage grooves, the upper end of the tubular member being formed to provide the drainage inlet.

In testimony whereof I sign this specification.

EDWARD W. N. BOOSEY.
